The ornamental design for the combined wire mesh faceguard and visor, as shown and described.

DESCRIPTION

FIG. 1 is a perspective view of the combined wire mesh faceguard and visor showing my new design;

FIG. 2 is a top plan view thereof;

FIG. 3 is a front elevation view thereof;

FIG. 4 is a bottom plan view thereof;

FIG. 5 is a side elevation view thereof; and,

FIG. 6 is a rear elevation view thereof.

The straps are shown broken away in FIGS. 1, 3, 5 and 6 and are understood to represent indeterminate length.
